UNITED STATES PATENT OFFICE

SAMPSON W. MOON, OF CHICAGO, ILLINOIS

ELECTRIC SAFETY RAZOR

Application filed January 12, 1928. Serial No. 246,115.

My invention relates to electric safety razors of the type disclosed in my Patent No. 1,592,309 of July 13, 1926, and the object is to produce a light, compact and simple structure which will be operated smoothly and powerfully by direct current with very little current consumption.

The various features of construction and arrangement of my invention are embodied in the device shown on the drawing in which:

Fig. 1 is a plan view,

Fig. 2 is an enlarged plan view with the enclosing shell partly in section,

Fig. 3 is an enlarged side view with the enclosing shell in section on plane 3—3 Fig. 1.

Fig. 4 is a view of the opposite side of the operative parts,

Fig. 5 is a section on plane 5—5 Fig. 3, and

Fig. 6 is a section on plane 6—6 Fig. 3.

A cylindrical electromagnet core 10 has the energizing winding 11 thereon. At its rear end the core is secured to the circular rear disk or plate 12 and its front end 13 is offset radially and is secured to the circular front disk or plate 14 by a screw 14'. The disks are in axial alignment and the core is relatively displaced radially so as to bring the surface of the winding close to one side of the cylindrical enclosing shell or grip 15 which slips over and receives the disks, and to leave space between the winding and shell for the armature structure. This structure comprises an armature bar 16 secured at its front end to a flat spring 17 secured to the front disk 14. Preferably the spring has the reduced or necked end 17' which extends through the hole 18 in the disk 14 and is securely riveted in place. The armature bar extends to within a short distance of the disk 14 and is secured to the spring by screws 19.

At its rear end the armature bar has the radial deflection 20 integral therewith and extending alongside of the corresponding core end, and the end 20' of this deflection is curved so as to reduce the magnetic resistance and to intimately engage along an extended area with the cylindrical core end when the armature is attracted by the energized core. The end of the armature bar swings between the cushion abutments 21 and 22 so that its

amplitude of vibration is limited. Normally the armature bar is held by the spring 17 adjacent to the abutment 21, and when attracted it will swing toward the abutment 22. These abutments may be sleeves of cushioning material, such as rubber, slipped on to pins 23 and 24 extending from the plate 12, and the abutments can therefore be very readily replaced when worn.

Secured to the rear plate 12 by screws 25 is a block or base 26 of insulating material, and extending through this block are the terminal pins 27 and 28. At its inner end the pin 27 is deflected radially and then axially, the radial section 27^a being received in the groove 29 in the block, and the axially extending section 27^b projecting beyond the inner side of the block for connection with the inner terminal 30 of the winding 11. The terminal pin 28 extends into the radial groove 31 in the block, its inner end being threaded to receive a securing nut 32. This nut also electrically secures to the pin the base 33 of the contact spring 34 which extends inwardly and terminates in a contact point 35 which normally is engaged by the contact pin 36 extending through but insulated from the armature bar, this pin being connected with the outer terminal 37 of the winding 11. An insulating washer 38 is inserted between the block 26 and the plate 12 to insulate the terminal pins and contact spring from the plate, and the plate has the clearance notches 39 and 40 through which the terminal pin 27 and the contact spring 34 respectively extend.

The terminal pins are engaged by the plug of a suitable connecting cord (not shown) and when current flows and the electromagnet is energized the armature will be attracted to withdraw the contact pin 36 from the spring 25 contact 35 to open the circuit whereupon the armature is released to reclose the circuit, the result being rapid vibration of the armature in a manner well known.

Extending axially outwardly through the opening 41 in the front plate 14 is the tool supporting post 42. At its inner end the post is of reduced diameter to be received and secured in the sleeve 43 at the end of the extension 44 on the spring 17. With this ar-

angement, when the armature is vibrated, the post will be given powerful, short, and rapid lateral vibration which will be communicative to a tool secured on the threaded end 45 of the post. The tool shown is a safety razor 46 which may be of any of the well known types, the tool having the threaded stem 47 for receiving the end 45.

It may be desirable to have the blade supporting tool vibrate longitudinally, or transversely, or diagonally, and for supporting it in adjusted position I provide a locking spring 48 on the end 45, the spring seating against the shoulder 49 on the end 45 and in the pocket 50 of the tool stem. The tool is screwed sufficiently on to the end 45 to compress the spring which will then lock the tool in the desired position for the desired vibration direction.

20 Secured by screws 51 to the front plate 14 is the head 52 of insulating material and this head has the axial passageway 53 through which the tool post extends. At its inner end the head is threaded to detachably receive 25 the front threaded end of the grip shell 15. The front end of the head is conical and at the end of the passageway 53 is the internal flange or shoulder 54 whose diameter is sufficiently greater than that of the tool post to afford 30 clearance for the post vibration. On the post is the soft rubber sleeve or bushing 55 which abuts against the shoulder 54. The external diameter of the bushing is less than the diameter of the passageway 53 so that the bushing 35 will not interfere with the vibration of the tool post. When the post is vibrated the soft rubber will readily yield but will always seal the gap between the post and the shoulder so that water or dust cannot enter the passageway 53.

At its rear end the grip sleeve 15 has the internal flange 56 forming the shoulder 57 and leaving the passage 58 for the terminal pins 27 and 28. To seal the grip sleeve against 45 the entrance of dust or moisture a soft rubber washer 59 is inserted between the shoulder 57 and the block 26 and to prevent distortion of the washer when the sleeve is applied, a thin smooth paper or metal washer 50 60 is interposed between the rubber washer and the block. The interior of the grip sleeve is thus fully protected against the entrance of moisture and the tool end can be dipped into water without endangering the operating parts and circuits within the grip.

To guide and gauge the adjustment of the tool, an arrow line 61 may be marked on the head 53. When the tool is parallel with this line it will vibrate longitudinally, and its 60 transverse or diagonal vibration can be readily gauged by means of the guideline.

It is evident that, instead of the type of shaving tool shown, other types of shaving tools and various types of massaging tools 65 may be applied to the tool supporting post.

I do not desire to be limited to the exact construction and arrangement shown as modifications are possible which would come within the scope of my invention.

I claim:

1. In an electric safety razor, the combination of end plates, an electromagnet core secured to and extending between said plates, an armature bar parallel with said core, a spring anchored to one of said plates and secured to one end of the armature bar to support said bar for vibration, said bar at its other end having a deflection extending transversely of the adjacent core end and being curved to fit the core end curvature when said core is energized, and a tool supporting post extending from the spring supported end of said bar to partake of the bar vibration.

2. In an electric safety razor, the combination of circular front and rear plates, an electromagnet core extending between said plates with its axis at one side of the plate axes, said core being secured to the rear plate, said front plate having an axial opening therethrough, the core at its front end being offset radially and secured to said front plate, an armature bar parallel with said core, a spring anchored to said front plate and secured to the front end of said armature bar to support said bar for vibration, the rear end of said bar being deflected radially to extend alongside of the rear end of said core and being curved to extend partly around said core when the armature bar is attracted, and a supporting post extending through said front plate opening and secured at its inner end to the front end of the armature bar to partake of the armature vibration, said post at its outer end being adapted to support a shaving tool.

3. In an electric safety razor, the combination of a front plate having an axial opening, a rear plate, an electromagnet core secured at its rear end to said rear plate, the front end of the core being deflected axially and secured to said front plate at one side of said axial opening, a spring anchored to and extending rearwardly from said front plate at the opposite side of said axial opening, an armature bar secured at its front end to said spring and being deflected at its rear end to extend alongside of the rear end of said core, a radial extension on said spring terminating in a sleeve, a tool supporting post secured at its rear end in said sleeve and extending through said axial opening, a winding for said core, and an electrical circuit controlling the current flow through said winding.

4. In an electric safety razor, the combination of a front plate having an axial opening, a rear plate, an electromagnet core having a winding and secured at its rear end to said rear plate, the front end of said core being axially offset and secured to the front plate at one side of said axial opening, an armature

structure flexibly secured to said front plate at the opposite side of said axial opening and extending rearwardly and being deflected radially at its rear end past the rear end of said core, a radial extension at the front end of said armature structure, a tool supporting post secured at its rear end to said extension and projecting through said axial opening, and contact means controlling the current flow through said winding.

5. In an electric safety razor, the combination of front and rear heads, said front head having an axial passageway, an electromagnet having a core secured at its ends to said heads, an armature structure flexibly anchored to said front head and being deflected at its rear end to be adjacent to the rear end of said core, a tool supporting post secured to the armature structure and extending forwardly through said axial passageway, a contact terminal on said armature structure connected with one terminal of the electromagnet winding, a terminal pin connected with the other terminal of said winding, a contact 25 spring supported on said rear head, a terminal pin connected with said spring, and a contact terminal on said spring cooperating with the contact terminal on said armature structure to control the current flow through 30 said winding.

6. In an electrical device of the class described, the combination of a grip structure having an axial opening at its front end, electromagnet mechanism within said structure comprising a core and energizing winding, an armature structure mounted within said grip structure to be vibrated by current variation in said electromagnet mechanism, a supporting post extending outwardly through said axial opening and connected with the armature structure to partake of the vibration thereof, means for securing a tool on the outer end of said post, an internal shoulder at the outer end of said opening surrounding said post, and a soft elastic packing sleeve intimately surrounding said post and engaging at its outer end against said shoulder to seal said opening against the entrance of moisture.

In witness whereof, I hereunto subscribe
50 my name this 4th day of January, 1928.
SAMPSON W. MOON.
